Primary Examiner — Ian Simmons*Assistant Examiner* — Janice Lim(57) **CLAIM**

The ornamental design for a cap for a dispenser, as shown and described.

DESCRIPTION

FIG. 1 is a top, front, left side isometric view of a cap for a dispenser, showing our new design;

FIG. 2 is a front elevational view thereof;

FIG. 3 is a rear elevational view thereof;

FIG. 4 is a left side elevational view thereof, and the right side elevational view being a mirror image thereof;

FIG. 5 is a top plan view thereof; and,

FIG. 6 is a bottom plan view thereof.

The broken line portions show unclaimed subject matter only and form no part of the claimed design.

The dot-dash broken lines on the cap of FIGS. 1-5 depict a boundary between the claimed and unclaimed portions only and form no part of the claimed design.
